(57) **CLAIM**

The ornamental design for a soundbar, as shown and described.

DESCRIPTION

FIG. 1 is a top, front, right perspective view of a soundbar showing new design;

FIG. 2 is a bottom, rear, left perspective view of the invention illustrated in FIG. 1;

FIG. 3 is a top view of the invention illustrated in FIG. 1;
FIG. 4 is a bottom view of the invention illustrated in FIG. 1;

FIG. 5 is a front view of the invention illustrated in FIG. 1;
FIG. 6 is a rear view of the invention illustrated in FIG. 1;
FIG. 7 is a right view of the invention illustrated in FIG. 1;
and,

FIG. 8 is a left view of the invention illustrated in FIG. 1.
The broken lines in the drawings represent portions of the soundbar that form no part of the claimed design.
